UNITED STATES PATENT OFFICE.

JOSEPH ASKINS, OF CHICAGO, ILLINOIS, ASSIGNOR TO PEERLESS LIGHT COMPANY, OF CHICAGO, ILLINOIS, A CORPORATION OF MAINE.

PULL-CHAIN SOCKET.

Application filed March 24, 1923. Serial No. 627,271.

To all whom it may concern:

Be it known that I, JOSEPH ASKINS, a citizen of the present Government of Russia, and a resident of Chicago, Cook County, Illinois, have invented certain new and useful Improvements in Pull-Chain Sockets, of which the following is declared to be a full, clear and exact description.

This invention relates to pull chain sockets and its principal object is to provide a pull chain socket which may be manufactured economically and which may be formed, in the main, of standard, commercial parts. Another object is to provide a pull chain socket composed in the main, of standard, commercial parts which may be readily assembled with other parts, to form a complete pull chain socket of the type which screws into the ordinary threaded electric light socket. Another object is to provide a pull chain socket of the type which screws into the ordinary electric light socket, which may be readily assembled and disassembled whereby the interior may be readily exposed in case it becomes necessary to repair or adjust parts thereof. With these and other objects and advantages in view, this invention consists in the several novel features hereinafter fully set forth and claimed.

The invention is clearly illustrated in the drawing accompanying this specification, in which:

Fig. 1 is a side elevation of a pull chain socket, embodying a simple form of the present invention; Fig. 2 is a side elevation, showing the three main elements of the socket detached from one another; Fig. 3 is a central, longitudinal section through the socket; Fig. 4 is an end or face view of the plug member of the socket; Fig. 5 is an end or face view of the socket member of the device, and Fig. 6 is a perspective view of one of the contact fingers employed in the construction of the device.

Referring to said drawing, the reference character 10 designates that member of a pull chain socket of the ordinary and well known construction, which contains the usual threaded shell 11 for the reception of an electric light bulb or a threaded plug, and 12 designates the switch mechanism of the socket member, which is of the usual and well known construction, operated by a

chain or cord 13, as is well understood. Standard commercial pull chain sockets have two terminals 14, 15 to which the ends of the usual house wires are connected by screws 16, 17.

18 designates an ordinary "push and pull" plug member having the usual threaded shell 19 and the usual center contact piece 20. As is customary in push and pull plugs, two parallel channels 21, 22 are formed in the plug in which channels are contact members 23, 24 that are secured respectively to the shell 19 and center contact piece 20. The parts thus far described are common and well known and require no further detailed description so far as this specification is concerned.

In constructing a pull chain socket in accordance with the present invention, I provide contact fingers 25, 26 which I secure to the terminals 14, 15, of the socket member, using the screws 16, 17 for this purpose. Said contact fingers have apertured end portions 27 through which the screws 16, 17 are inserted and have other portions 28 that extend at right angles to the end portions 27 and lie against the end face of the porcelain or other non-conducting body portion of the socket member 10. Projecting from the part 28 of each finger is a contact piece 30 which projects from the end face 29, and the two contact pieces 30 are arranged parallel with each other and enter the channels 21, 22 of the plug member 18 and make contact with the contact pieces 23, 24 thereof.

The socket member 10 and plug member 18 are positively connected together by a thimble like or ferrule like connection 31 which has a central aperture through which the plug member extends, and an overhanging flange like part 32 which overhangs a shouldered portion 33 of the plug member 18. The connecting member 31 and outer casing 34 of the socket member 10 have means which co-act with each other to secure the member 31 upon the socket 10 and for this purpose the usual depressed lugs 35 are provided in the connecting member 31 which enter holes 36 in the casing 34.

The parts are assembled by inserting the contact members 30 of the fingers 25, 26 into the channels 21, 22 of the plug member 18 and thereafter slipping the ferrule like connecting member 31 over the plug

member 18 and engaging the lugs 35 of said member 31 in the holes 36 of the shell 34 of the socket member 10.

In its assembled condition, the pull chain 5 socket may be screwed into the ordinary electric light socket, and an electric light bulb or a screw plug may be screwed into the threaded shell 11 of the socket 10, and the current to said bulb or plug may be controlled by the switch mechanism as usual. Furthermore a pull chain socket member provided with the contact fingers 25, 26 may be used in connection with a stationary push and pull socket, although it is preferred to use the device in its fully assembled condition.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new and desire to secure by Letters Patent:

1. A pull chain socket, comprising in combination a pull chain socket member, having pull chain switch elements, including two

terminal members, two contact fingers secured to the said terminal members, a push and pull plug member having a center contact piece and an external threaded contact shell, and having internal electric contact members leading from said centre contact piece and from said threaded shell and contacting with said contact fingers of the socket, and a ferrule like connecting member having portions co-acting with the socket member and plug member for securing them together.

2. A pull chain socket, comprising in combination a pull chain socket member, having pull chain switch elements, including two terminal members, and two contact fingers secured to the said terminal members, a push and pull plug member having a centre contact piece and an external threaded contact shell, and having internal electric contact members leading from said centre contact piece and from said threaded shell, and contacting with said contact fingers of the socket, said push and plug member having a shouldered end, and a ferrule like connecting member having a flange overhanging said shoulder, and lugs engaging in holes in the socket member.

JOSEPH ASKINS.
